UNITED STATES PATENT OFFICE.

EUGENE J. RAY, OF BEVERLY, MASSACHUSETTS, ASSIGNOR TO UNITED SHOE MACHINERY CORPORATION, OF PATERSON, NEW JERSEY, A CORPORATION OF NEW JERSEY.

SKIVING MACHINE.

Application filed December 12, 1922. Serial No. 606,445.

To all whom it may concern:

Be it known that I, EUGENE J. RAY, a citizen of the United States, residing at Beverly, in the county of Essex and State of Massachusetts, have invented certain Improvements in Skiving Machines, of which the following description, in connection with the accompanying drawings, is a specification, like reference characters on the drawings indicating like parts in the several figures.

This invention relates to skiving and splitting machines and is herein illustrated as embodied in a skiving machine of the type which is provided with a rotary cylindrical knife.

Skiving machines having cylindrical knives are commonly provided with a driven feed roll located partly within the knife and adjacent the upper portion thereof and with a co-operating presser located above the feed roll and outside the knife. The presser, which may also be in the form of a roll, is adjustable angularly to vary the inclination of the scarf which will be produced, the feed roll being mounted for yielding movement both away from the edge of the knife and angularly so as to respond both to the thickness of the work and to the angular position of the presser. This construction and arrangement is satisfactory when ordinary upper leather and similar material is being operated upon but when an attempt is made to operate upon thicker, heavier material, for example upon the casings of automobile tires, a difficulty is encountered in that the material is not gripped with sufficient force over a sufficient area to ensure proper feeding.

According to the present invention the presser and the feed roll are both adjustable and are so mounted that they may be adjusted in unison whereby they maintain the same relation to each other in any position to which they may be adjusted. In the illustrative machine the presser and the feed roll are both mounted upon an adjustable bracket, the feed roll being urged toward the presser at all times by a comparatively strong spring. When it is desired to vary the inclination of the scarf, the bracket is adjusted, and with it the presser and roll are adjusted in unison. Their operative faces are thus always parallel to each other, and uniform and sufficient pressure is at all

times exerted upon an area of the work sufficient to ensure a steady and adequate feed. Preferably the axis about which the bracket is adjusted is substantially parallel to the direction of feed of the work and passes substantially through that point at one end of the feed roll which, at any given moment, is in position to engage the work. This point, therefore, remains always in the same position with respect to the knife, and no adjustment of the roll bodily toward or from the knife is necessary.

These and other features of the invention including certain details of construction and combinations of parts will be described as embodied in an illustrative machine and pointed out in the appended claims.

Referring to the accompanying drawings, Figure 1 is a front elevation of one end of a machine in which the present invention is embodied.

Figure 2 is an end elevation of the same portion with part of the wall of the swinging head and part of the roll-supporting web broken away, and

Figure 3 is a detail principally in elevation showing more particularly the mounting of the roll.

The general structure of the illustrative machine is or may be like that of the machine shown in the patent to La'tham 1,301,283; and before describing the new construction those features which are the same or substantially the same as the corresponding ones of the patented machine will be briefly indicated. The machine comprises a frame or base 7 in which are bearings for a rotary shaft 9 upon the outer end of which a cylindrical knife 11 is mounted. Pivoted about a vertical axis (not shown) which is located at the farther side of the machine as viewed in Fig. 1, is a head 13 which, in the operative position shown, forms a continuation of the frame or base 7. This head 13 carries among other elements the feed roll 15, the purpose of pivoting the head to the frame in the manner described being to permit the head to be swung out of the way to give access to the knife as well as to the parts carried by the head. The head is normally held in the operative position illustrated by a latch (not shown) which may be released at any time by pulling down on a lever 17 preparatory to swinging the head to one side; and,

when this lever is pulled down, a cam 19 formed upon the rock-shaft 21, to which one end of the lever is attached, acts upon a tail 23 of the pivoted yoke which carries the feed roll in such manner that the roll is lowered from the adjacent edge of the knife. A presser foot 25 co-operates with the feed roll to advance the work to the knife. The knife and feed roll of the machine as well as the knife grinding mechanism (not shown) may be driven in any suitable manner as for example the manner of the patented machine. No further details of construction and mounting of the parts which have been thus far described, except those of the presser foot and feed roll, will be given, reference being made to the patented machine. It will be understood, however, that the work is fed from left to right, as viewed in Fig. 1, to skive or to split a piece of sheet material.

In the patented machine the presser is mounted at the end of an arm which is rigid with the base of the machine. In the present machine the presser is mounted upon an angularly adjustable bracket 27 upon which the feed roll is also mounted, the bracket being carried by the head 13 so that when this head is swung to one side, it carries with it both the feed roll and the presser. Formed on the left hand wall of the head 13, as viewed in Fig. 1, are two segmental ribs 29 to provide a guideway in which is received a segmental guide 31 rigid with the bracket 27. This guide has formed upon it a segmental rack 33 which meshes with a pinion 35, the curvature of the segmental guide and guideway being such that, when the pinion is rotated by means of the hand-hold 37, the bracket is swung angularly about a horizontal axis which passes through a point 39 in the upper right-hand edge of the feed roll, as viewed in Fig. 2. The rack and pinion are held in mesh by a screw 41 the stem of which passes through an arcuate slot 43 in the front wall of the head 13 and is threaded into the guide 31. In the position of parts shown, the bracket 27 is in its extreme upper position. In order to adjust it, the hand-hold 44 on the outer end of the screw 41 is turned to loosen the screw, and then the hand-hold 37 is turned to adjust the bracket.

As has been explained above, the feed roll 15 is carried by the bracket 27 and is therefore adjusted angularly with the presser. Extending from the lower right-hand portion of the bracket 27, as viewed in Fig. 2, is a projection or web 127 having in its upper portion a boss threaded to receive a set-screw 45 which determines, in a manner presently to be described, the normal position of the feed roll by limiting the extent of angular movement imparted to the roll by the roll-supporting spring. Extending at right angles to the web 127 is a second web

227 (Fig. 1) having a horizontally extending boss 327 and a depending vertically extending socket 427. Through a bearing in the horizontally extending boss 327 extends a rock shaft 47 to which is fast the yoke 70 which carries the feed roll, said yoke having, as has been explained above, the depending tail 23. This yoke comprises bosses 51, 53 with the former of which the tail 23 is integral, said bosses being pinned to the 75 rock-shaft 47 and having upstanding lugs 55, 57 to which are fastened by screws 59, 61 the arms 63, 65 of the yoke, the feed roll 15 being fast to a shaft 67 having bearings in the arms of the yoke, which shaft is driven 80 as in the machine of the Latham patent. Located in the vertically depending socket 427 is a coiled spring 69 which, at its lower end, rests upon the upper end of a tension-varying screw 71 threaded into the lower 85 end of the socket. The upper end of the spring rests against the under side of a portion of the yoke which carries the feed roll and tends at all times to swing the roll upwardly about the axis of the rock-shaft 47, 90 the extent of this upward movement—and consequently the normal position of the roll—being determined by the position of the screw 45, mentioned above, the end of which contacts with another portion of the 95 feed roll carrying yoke, this last named portion being a bar 73 (Fig. 3) which connects the lugs 55, 57 by which the arms of the feed roll yoke are carried. The screw 45 is provided with a hand-hold 74, by which it may 100 be adjusted, and with a lock-nut 75 by which it may be held in adjusted position. The spring 69 tends at all times to urge the feed roll toward the presser, the limit of its movement in that direction being limited by 105 the stop-screw 45. As soon as a piece of work enters between the roll and presser, the roll is forced downwardly, and during the skiving operation the work is firmly gripped and fed. The construction and arrangement 110 of the parts is such that the work-engaging surfaces of the presser and roll are substantially parallel; and, since these two members are carried by the same bracket, this substantially parallel relation is maintained at 115 all times.

Having thus described my invention, what I claim as new and desire to secure by Letters Patent of the United States, is:

1. A machine of the class described having, in combination a knife and means for engaging and advancing to the knife a piece of work, said means including a pair of feed members arranged to engage the work one on each side thereof, a carrier for said members, and means whereby the carrier may be adjusted angularly in a path the plane of which is at an angle to the direction of feed movement of the work.

2. A machine of the class described hav-

ing, in combination, a knife, means for operating the knife, a pair of feed members for engaging the work one on each side thereof and advancing it to the knife, said members being angularly adjustable, and connections between the members such that they are adjusted in unison.

3. A machine of the class described having, in combination, a knife, means for operating the knife, a pair of feed members for engaging the work one on each side thereof and advancing it to the knife, said members being angularly adjustable, and connections between the members such that their relative position with respect to each other remains unchanged.

4. A machine of the class described having, in combination, a knife, means for operating the knife, a pair of feed members for engaging the work one on each side thereof and advancing it to the knife, said members being angularly adjustable in a path the plane of which is at right angles to the direction of feed movement of the work.

5. A machine of the class described having, in combination, a knife, means for operating the knife, a presser and a feed roll located one above the other and arranged to engage respectively the upper and the lower side of the work, and a carrier upon which the presser and feed roll are mounted, said carrier being angularly adjustable about an axis which is substantially parallel to the direction of feed movement of the work.

6. A machine of the class described having, in combination, a knife, means for operating the knife, a presser and a feed roll located one above the other and arranged to engage respectively the upper and the lower side of the work, and a carrier upon which the presser and feed roll are mounted, said carrier being angularly adjustable about an axis which is substantially parallel to the direction of feed movement of the work and passes substantially through a point at one end of the roll and close to the edge of the knife.

7. A machine of the class described having, in combination, a cylindrical knife, means for rotating the knife, a feed roll located partly within the knife and close to the upper portion of the edge thereof, a presser located outside the knife above the feed roll, a carrier upon which the feed roll and presser are mounted, and means whereby the carrier may be adjusted angularly about an axis which is substantially parallel to the direction of feed movement of the work.

8. A machine of the class described having, in combination, a knife, a presser, a feed roll, a bracket upon which both the presser

and feed roll are mounted, a carrier for the roll, a spring acting between the bracket and the roll carrier to urge the roll toward the presser, and means whereby the bracket may be adjusted angularly.

9. A machine of the class described having, in combination, a knife, a presser, a feed roll, a bracket upon which both the presser and feed roll are mounted, a carrier for the roll, a spring acting between the bracket and the roll carrier to urge the roll toward the presser, and means whereby the bracket may be adjusted angularly about an axis which is approximately parallel to the direction of feed of the work and passes substantially through a point at one end of the roll which, at any given moment, is in position to engage the work.

10. A machine of the class described having, in combination, a frame, a rotary shaft carried thereby, a knife mounted on the shaft, a head capable of swinging away from the frame, a bracket carried by the head, and a presser and feed roll carried by the bracket.

11. A machine of the class described having, in combination, a frame, a rotary shaft carried thereby, a cylindrical knife mounted on the shaft, a head capable of swinging away from the frame, an adjustable bracket carried by the head, and a presser and feed roll carried by the bracket.

12. A machine of the class described having, in combination, a knife, means for engaging and advancing to the knife a piece of work, said means including a pair of feed members arranged to engage the work one on each side thereof, a carrier for said members, means connected with one of said members for driving it, and means whereby the carrier may be adjusted angularly in a path the plane of which is at an angle to the direction of feed movement of the work while maintaining the driving connection operative.

13. A machine of the class described having, in combination, a cylindrical knife, means for rotating the knife, a presser and a feed roll located one above the other and arranged to engage respectively the upper and lower side of the work, means connected with the roll for driving it, and a carrier upon which the presser and feed roll are mounted, said carrier being angularly adjustable about an axis which is substantially parallel to the direction of feed movement of the work while maintaining the driving connection operative.

In testimony whereof I have signed my name to this specification.

EUGENE J. RAY.

DISCLAIMER.

1,479,832.—*Eugene J. Ray, Beverly, Mass.* SKIVING MACHINE. Patent dated January 8, 1924. Disclaimer filed March 27, 1926, by the assignee, *United Shoe Machinery Corporation*.

Hereby enters this disclaimer to said claims 1, 2, 3, 4, 5, 6, and 12 of said Letters Patent, which are in the following words, to wit:

“ 1. A machine of the class described having, in combination a knife and means for engaging and advancing to the knife a piece of work, said means including a pair of feed members arranged to engage the work one on each side thereof, a carrier for said members, and means whereby the carrier may be adjusted angularly in a path the plane of which is at an angle to the direction of feed movement of the work.

“ 2. A machine of the class described having, in combination, a knife, means for operating the knife, a pair of feed members for engaging the work one on each side thereof and advancing it to the knife, said members being angularly adjustable, and connections between the members such that they are adjusted in unison.

“ 3. A machine of the class described having, in combination, a knife, means for operating the knife, a pair of feed members for engaging the work one on each side thereof and advancing it to the knife, said members being angularly adjustable, and connections between the members such that their relative position with respect to each other remains unchanged.

“ 4. A machine of the class described having, in combination, a knife, means for operating the knife, a pair of feed members for engaging the work one on each side thereof and advancing it to the knife, said members being angularly adjustable in a path the plane of which is at right angles to the direction of feed movement of the work.

“ 5. A machine of the class described having, in combination, a knife, means for operating the knife, a presser and a feed roll located one above the other and arranged to engage respectively the upper and the lower side of the work, and a carrier upon which the presser and feed roll are mounted, said carrier being angularly adjustable about an axis which is substantially parallel to the direction of feed movement of the work.

“ 6. A machine of the class described having, in combination, a knife, means for operating the knife, a presser and a feed roll located one above the other and arranged to engage respectively the upper and the lower side of the work, and a carrier upon which the presser and feed roll are mounted, said carrier being angularly adjustable about an axis which is substantially parallel to the direction of feed movement of the work and passes substantially through a point at one end of the roll and close to the edge of the knife.

“ 12. A machine of the class described having, in combination, a knife, means for engaging and advancing to the knife a piece of work, said means including a pair of feed members arranged to engage the work one on each side thereof, a carrier for said members, means connected with one of said members for driving it, and means whereby the carrier may be adjusted angularly in a path the plane of which is at an angle to the direction of feed movement of the work while maintaining the driving connection operative.”

[*Official Gazette April 13, 1926.*]
